UNITED STATES PATENT OFFICE.

WESLEY F. ROSCOE, OF UPPER MATTOLE, CALIFORNIA.

SCREEN-FASTENER.

1,084,167.

Specification of Letters Patent.

Patented Jan. 13, 1914.

Application filed April 30, 1913. Serial No. 764,648.

To all whom it may concern:

Be it known that I, WESLEY F. Roscoe, a citizen of the United States, residing at Upper Mattole, in the county of Humboldt and State of California, have invented a new and useful Screen-Fastener, of which the following is a specification.

This invention aims to provide novel means for actuating the stop strip of a screen frame, whereby the same may be made to coöperate properly with the frame of the window.

One object of the invention is to provide a device of this type, in which the stop strip is so supported that it may swing, intermediate its ends, thereby permitting the stop strip to engage properly with the side portion of a window frame which is not in the form of a true rectangle.

It is within the scope of the invention, to improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings:—Figure 1 shows the invention in front elevation; Fig. 2 is a fragmental rear elevation; Fig. 3 is a transverse section on the line 3—3 of Fig. 2; Fig. 4 is a fragmental top plan showing one corner of the screen frame; and Fig. 5 is a perspective of the actuating member for the stop strip.

In carrying out the invention there is provided a frame 1, supporting a screen 16, one of the upright stiles of the frame 1 being designated specifically by the reference character 2. The stile 2 is equipped with a longitudinal recess 3 in which is mounted to slide a stop strip 4. A cap plate 5 is secured by nails 6 or any other suitable means, to the upper end of the stile 2 and extends outwardly above the upper end of the stop strip 4.

The stile 2 is provided with openings 7 in which are mounted to slide securing elements which may be screws 8, the screws 8 entering the inner edge of the stop strip

4. In its inner edge, the stop strip 4 is equipped with a recess 9, at one end of which is formed a shoulder 10.

An actuating member is provided for moving the stop strip 4 outwardly, and this actuating member may be of any desired form. In the present instance, the actuating member is shown in the form of a wedge 11, which is delineated in detail in Fig. 5. The wedge 11 is mounted to slide between the inner edge of the stop strip 4 and the outer edge of the stile 2 and is adapted to be received in the recess 9 in the stop strip. The wedge 11 is provided with an outstanding shank 12 which preferably is of polygonal contour, the shank 12 registering slidably in a longitudinal slot 14, extended through the stile 2. At its outer end, the shank 12 is provided with a head 15 which may be of any desired form, the head 15 and the wedge 11 lying upon opposite sides of the stile 2, as will be understood readily when Figs. 1 and 2 are compared.

When the wedge 11 is actuated in one direction by means of the head 15, the wedge will press against the stop strip 4 and move the same outwardly, so that the stop strip 4 will coöperate properly with one side of the window frame. During this operation, the securing elements 8 will slide in the openings 7, the heads of the securing elements constituting means for limiting the outward transverse movement of the stop strip 4. It is to be observed that when the stop strip 4 is in the advanced position shown in Fig. 2, the shoulder 10 in the stop strip rests upon the slant face of the wedge 11. The shoulder 10, therefore, constitutes a fulcrum, whereby the stop strip 4 is permitted to tilt transversely upon the wedge 11, and as a consequence, the stop strip and also the rest of the screen frame will fit against the frame of the window properly even though the frame be out of plumb.

Having thus described the invention, what is claimed is:—

1. In a device of the class described, a frame; a stop strip slidable upon the frame; means for slidably connecting the stop strip with the frame; and means movable longitudinally of the frame for actuating the stop strip transversely with respect to the frame.

2. In a device of the class described, a frame; a stop strip mounted to slide transversely with respect to the frame; and actu-

ating means supported by the strip only and abutting against the inner edges of the strip and the frame for moving the stop strip outwardly, the stop strip being mounted to tilt transversely with the actuating means as a rigid fulcrum, thereby permitting the stop strip to assume different angles with respect to the frame.

3. In a device of the class described, a frame; a stop strip slidably connected therewith and a wedge slidably mounted between the stop strip and the frame.

4. In a device of the class described, a frame; a stop strip mounted to slide thereon; and a slidably mounted wedge interposed between the stop strip and the frame, the stop strip having a wedge-receiving recess, one edge of which constitutes a shoulder, which, engaging the wedge, permits the stop strip to swing transversely and to assume different angles with respect to the frame.

5. In a device of the class described, a frame; a stop strip slidable transversely of the frame; connecting elements slidable in the frame and adapted to engage the frame, the connecting elements being adjustably united with the stop strip; and rigid, mov-

able means engaging the frame and the stop strip between the connecting elements to move the stop strip transversely with respect to the frame.

6. In a device of the class described, a frame comprising a stile having a recess; a stop strip slideable in the recess and provided at its inner edge with a tapered opening, one end of which defines a shoulder; screws slideable in the stile and threaded into the stop strip; a wedge slideable between the stile and the stop strip, and adapted to register in the opening, the shoulder being adapted to engage the slant face of the wedge to permit the stop strip to tilt with respect to the stile, the wedge being provided with a shank extended through the stile, and the stile being provided with an elongated opening in which the shank is adapted to move.

In testimony that I claim the foregoing as my own, I have hereto affixed my signature in the presence of two witnesses.

WESLEY F. ROSCOE.
